Primary Examiner — Elizabeth J Oswecki

(57) **CLAIM**

The ornamental design for a light, as shown and described.

DESCRIPTION

FIG. 1 is a perspective view of a light showing new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is another perspective view thereof, where the light is in a configuration of use illuminated and attached to a circular knob and chain shown in broken lines.

The broken lines in the drawings depict portions of the light that form no part of the claimed design.
